UNITED STATES PATENT OFFICE

106,917

DESIGN FOR A TEXTILE FABRIC OR SIMILAR ARTICLE OF MANUFACTURE

Bruno Haertel, Providence, R. I., assignor to A. D. Juilliard & Co., Inc., New York, N. Y., a corporation of Delaware

Application February 14, 1936, Serial No. 61,176

Term of patent 3½ years

To whom it may concern:

Be it known that I, Bruno Haertel, citizen of Poland, residing at Providence, Rhode Island, have invented a new, original, and ornamental Design for a Textile Fabric or Similar Article of Manufacture, of which the following is a specification, reference being had to the accompanying drawing, forming part thereof.

The figure is a plan view of the textile fabric or similar article of manufacture showing my new design. The design illustrated consists of a background having thereon a multiplicity of spaced apart raised stripes each of which has at intervals therealong threads producing nub-effects therein.

I claim:

The ornamental design for a textile fabric or similar article of manufacture substantially as shown and described.

BRUNO HAERTEL.
